Patented Feb. 22, 1927.

UNITED STATES PATENT OFFICE.

CHARLES C. RITZ, OF FOREST HILLS, NEW YORK.

CONTROL FOR MUSIC-BOX MOVEMENTS.

Application filed November 2, 1925. Serial No. 66,145.

My invention relates to a new and improved control for music box movements.

One of the objects of my invention is to devise a control for music box movements which is very sensitive and can be operated by the use of very slight force.

Another object of my invention is to devise a control which will release a music box movement so as to permit the playing of 10 a tune or a portion of a tune, for a predetermined period.

Another object of my invention is to devise a control of this type which can be actuated by coins of various sizes and 15 weights.

Another object of my invention is to devise a control which shall be extremely simple, cheap and compact, and which will require a minimum number of moving parts.

20 Other objects of my invention will be set forth in the following description and drawings, which illustrate a preferred embodiment thereof, it being understood that the above general statement of the objects of my 25 invention is intended to generally illustrate the same and not to limit it in any manner.

Fig. 1 is a vertical sectional view on the line 1-1 of Fig. 3 showing my device applied, for example, to a toy bank, although I 30 do not limit the field of use of my invention in any manner.

Fig. 2 is a section on the line 2-2 of Fig. 3.

Fig. 3 is a section on the line 3-3 of 35 Fig. 2.

The toy bank B or the like is provided with a lower portion separated from the upper part thereof, in which the music box movement is mounted, by a partition BA 40 having a mouth 23 through which the coins can enter the lower part of the device. The lower part of the device forms the coin receptacle having a door D which can be closed or locked in any suitable manner.

45 The spring motor M is of the ordinary type and it can be wound by means of an ordinary key W which projects through the rear wall of the apparatus. The spring motor M is provided with an ordinary crown gear M' which meshes with a spur gear M₂, the last mentioned gear being connected to the shaft of the drum 10 carrying the teeth 11.

This shaft also has a large gear 13 connected thereto, and the last mentioned gear 55 meshes with a smaller gear 14 mounted upon

a short shaft upon which the gear 15 is also mounted. The gear 15 meshes with a smaller gear 16 mounted upon a second shaft upon which the spur gear 17 is also mounted. The last mentioned gear 17 meshes with a screw 18, which is more clearly shown in Fig. 3, and the fan brake or governor 19 is connected to the screw 18.

This part of the music box movement can 65 be of any well known type, as the purpose thereof is to revolve the fan 19 at a very high velocity so that the resistance of the air to the revolution of the said fan 19 acts as a govenor to control the speed of revolution 70 of the drum 10. The reeds 12 are of the well known type.

A control member 22 is mounted upon the shaft of the drum 10. As shown in Fig. 1, this control member 22 has the ends thereof 75 obliquely inclined to the top and bottom thereof.

The ends of the control member 22 are adapted to engage the springy end piece 21' which is connected to the inner end of the 80 detent 20. This detent 20 consists of a single piece of bent wire which is pivotally mounted in the sleeve S, which is connected to the base of the combs by means of a 85 screw 30.

The detent 20 is also provided with an inclined flange 21 which is mounted upon the forwardly projecting part of the said detent wire 20.

As shown in Fig. 1, the detent can be 90 moved towards and away from the vertical base of the apparatus. When the member 22 engages the springy end member 21' of the detent, the revolution of the drum causes the detent wire 20 to be turned so that the 95 bent end thereof engages the fan 19 and prevents the turning of the drum 10. If, however, the member 21 is forced towards the base of the apparatus, as, for example, by means of a coin C, then the springy end 21' 100 of the detent yields sufficiently so that it passes beyond the member 22, thus releasing the drum 10 so that it is free to revolve. When the drum has made substantially a complete revolution, the member 22 again 105 engages the springy member 21' so as to move the detent wire 20 into the operative position.

It is therefore obvious that the introduction of each coin into the bank B causes the 110 tune to be played for a short and predetermined period, so that the spring motor will

not run down until a large number of coins have been introduced into the bank.

It is obvious that in order to apply my improvement to any existing type of music box movement, that it is only necessary to provide a single bent wire having the member 21 which can be made of any light metal, and the spring member 21' which can be made of any cheap springy metal, the only other change which is necessary being the affixing of the member 22 upon the shaft of the drum.

It is therefore obvious that the device is of maximum simplicity, cheapness and compactness.

It is to be understood that this device can be applied to a toy bank or the like in a great many different ways, and that I do not restrict the use of the movement in any particular position or in any particular location, as the above mentioned drawings and description are intended to be illustrative.

I have described a preferred embodiment of my invention, but it is clear that numerous changes and omissions could be made without departing from its spirit.

For example, the flange 21 could be mounted adjacent the bottom of a coin chute because the control is so sensitive that the impact of a falling coin is sufficient to operate it.

I claim:—

1. In combination with a music box movement or the like having a drum the revolution of which is adapted to cause the playing of a tune, a revolute member adapted to revolve in unison with said drum, a detent member adapted to engage the said revolute member, a springy member connected to said detent member, and a control member adapted to revolve in unison with the said drum and adapted to engage the said springy member to actuate said detent member to move said detent member into engagement with said revolute member, the said springy member being sufficiently yieldable so that it can be forced out of engagement with the said control member.

2. A device according to claim 1 in which the said control member has end faces which make oblique angles with the other faces thereof.

3. A device according to claim 1 in which the music box movement is mounted in a casing having an opening adapted to admit coins, and the said detent member has a flange connected thereto and located adjacent the inner end of the said opening for direct engagement by an inserted coin while said coin is being forced through said opening.

4. A device according to claim 1 in which the music box movement is mounted in a

casing having an opening adapted to admit coins, and the said detent member has a flange connected thereto and located adjacent the inner end of the said opening for direct engagement by an inserted coin while said coin is being forced through said opening, the said flange being inclined to the axis of the said opening.

5. In combination with a music box movement comprising a plurality of reeds adapted to co-operate with teeth mounted upon a revolute drum, a motor adapted to actuate the said drum, a fan connected to the said motor by intermediate gearing, a revolute control member mounted upon the shaft of the said drum and adapted to revolve in unison therewith, and a detent member pivotally mounted upon the base of the said reeds, the said detent member having one end thereof adapted to engage the said fan, the other end of the said detent member having a resilient member connected thereto, the said control member being adapted to engage the springy member, the said resilient member being sufficiently yieldable that it can be forced out of engagement with the said control member, and a coin slot adjacent one end of said resilient member so that an entering coin is adapted to positively actuate said resilient member.

6. In combination, a casing having an opening adapted to admit coins, a music box movement mounted in said casing and having a plurality of reeds adapted to co-operate with a revolute drum having teeth adapted to engage the said reeds, a motor in said casing adapted to actuate the said drum, a fan in the said casing and mounted on a shaft connected to the said motor by intermediate gearing, a revolute control member mounted on the shaft of the said drum and a detent member comprising a single bent wire pivotally mounted upon the base of the said reeds, the said wire having one end thereof adapted to engage the said fan and having the other end thereof provided with a springy member, the intermediate portion of the said wire being bent away from the reeds, drum and motor, a flange connected to the said intermediate bent portion of the detent member and substantially aligned with the axis of the said opening, the said flange being moved with respect to said opening when a coin is admitted into said casing through said opening, the said springy member being sufficiently yieldable so that it can be forced out of engagement with the said control member by the action of a coin which is admitted into the casing through the said opening.

In testimony whereof I affix my signature.
CHARLES C. RITZ.
